(57) **CLAIM**

The ornamental design for a surgical implant extraction jaw, as shown and described.

DESCRIPTION

FIG. 1 is a perspective view of a surgical implant extraction jaw in accordance with my new design;

FIG. 2 is a front view of the surgical implant extraction jaw of FIG. 1;

FIG. 3 is a rear view of the surgical implant extraction jaw of FIG. 1;

FIG. 4 is a left side view of the surgical implant extraction jaw of FIG. 1;

FIG. 5 is a right side view of the surgical implant extraction jaw of FIG. 1;

FIG. 6 is a top view of the surgical implant extraction jaw of FIG. 1; and,

FIG. 7 is a bottom view of the surgical implant extraction jaw of FIG. 1.

In the drawings, the dashed broken lines shown in FIGS. 1-7 illustrate portions of the surgical implant extraction jaw that form no part of the claimed design. The dash-dot broken lines shown in FIGS. 1, 4, 5, 6 and 7 illustrate the bounds of the claim and form no part of the claimed design.
